BRAKE GEAR MOUNTING

Filed May 9, 1927

Inventor:
Arthur F. O'Connor,
By Dennis Manning.
Attest.

UNITED STATES PATENT OFFICE.

ARTHUR F. O'CONNOR, OF CHICAGO, ILLINOIS, ASSIGNOR TO UNION RAILWAY EQUIPMENT COMPANY, OF CHICAGO, ILLINOIS, A CORPORATION OF ILLINOIS.

BRAKE-GEAR MOUNTING.

Application filed May 9, 1927. Serial No. 189,795.

The mounting of the present invention is designed to meet the requirements of gearing of the type now commonly in use in connection with hand brakes for freight cars in which provision is made for the mounting and journaling of a pinion on the lower end of the 5 brake shaft which meshes with a large gear mounted on the winding shaft for the brake chain. In brake gear mountings intended for this service, it has been customary to employ fittings and connections designed with 10 reference to the particular or specific construction of the car for which the gear mounting was intended, and in most cases the 15 mounting has been bolted, braced, angled, or otherwise secured to the longitudinal and cross sills of the car frame in some manner special to the framing of some particular type of car.

20 The present invention is so designed that it may be readily applied to cars of practically any standard type, since the mounting is designed to be connected with the under body frame only at the end sill and is elsewhere connected and supported from the car 25 floor. In view of the fact that the mounting is thus secured to the car frame at only a single point, the present mounting is adapted for general use under conditions which 30 would preclude the use of mountings specially designed to fit into the under body structure of some particular type of car.

A further object of the invention is to simplify the construction and method of securing, and at the same time make full and adequate provision for the strains and thrusts incidental to the employment of the device in actual service.

Further objects and details will appear 40 from the description of the invention in conjunction with the accompanying drawings wherein—

Figure 1 is a front end elevation of the mounting secured to the front of the car;

Fig. 2 is a side elevation of the mounting showing the car floor and end wall in section;

Fig. 3 is a top plan view of the mounting; and

Figs. 4 and 5 are details showing variations 50 in the form of the frame for the mounting.

The gear assembly for which the mounting is provided comprises a driving pinion 10 mounted upon the lower end of the main

brake shaft 11, which pinion meshes with a large winding gear 12 mounted at the upper 55 end of a winding drum or shaft 13. These features are common in the construction of this type of brake gearing and need not be further described in detail.

The gear and pinion are mounted within a 60 gear housing open at its under side and comprising a top plate 14 provided with a depending flange 15, the general configuration 65 of the flange being circular with a protrusion 16 at its medial forward side for the purpose of housing the small driving pinion. The top plate 14 of the gear housing is of 70 rectangular formation, so that it protrudes at its corners beyond the peripheral flanged wall of the housing, and the top plate is provided 75 along each of its side edges with an upstanding flange 17, which flanges are riveted between and to the downwardly extending 80 flanges 18 of a pair of parallel angle bars 19 which comprise the supporting frame and 85 which may be separated and disconnected at their rear ends, although it is preferred to make the frame continuous and to give it either the U-shape configuration indicated in Fig. 4, or the rectangular configuration indicated in Fig. 5.

In the form shown in Fig. 4, the lateral 85 flanges 20 of the angle bar frame are carried continuously around the curved rear end of the frame, while, as shown in Fig. 5, the flanges are notched out at the corners 21 leaving a separated rear flange 22. The lateral 90 flanges of the supporting bar, however, are provided with bolt holes 23 for the reception of bolts 24 which are entered through the 95 floor 25 of the car and secured by means of nuts 26, or in any other suitable manner.

The forward ends of the supporting frame members protrude forwardly beyond the front wall 27 of the car and under the front 95 cross sill 28 to which the horizontal flanges of the frame members are secured by rivets 29, or in any other suitable manner. The connection is further reinforced by the provision of a front angle plate 30, the vertical 100 flange of which is secured to the wall 27 and the vertical flange of the end sill angle 28 by rivets 31, while the horizontal flange 32 is secured by rivets 33, thereby anchoring and reinforcing the forward protruding end of 105 the supporting frame in a rigid and substan-

tial manner. The reinforcing frame extends inwardly under the car to a much greater distance than the gear housing, the medial portion of which lies directly under the front wall of the car, and this method of extending the supporting frame and securing it directly to the car floor obviates the necessity for deriving support from any portion of the under body frame other than the front sill, and at the same time distributes the strains throughout a considerable portion of the car floor, so that the latter will be easily able to support the load.

The lower end of the drum or winding shaft 13 is journaled through the web 34 of a hanger bracket comprising side legs 35 and a medial front leg 36 reinforced by ribs 37, which legs at their upper ends merge into a substantially half circular rim 38 provided at its center front with an extension 39 configured to underlie the protruding wall flange 16 of the gear housing and having laterally disposed lugs 39^a which register with similarly positioned lugs 40 on the gear housing to which it is connected by means of vertical bolts 41 which also extend upwardly through the front corners of the top wall of the housing.

The main portion of the bracket rim follows the curvature of the main portion of the gear housing, and the rim is provided near each end with an outwardly projecting ear or lug 42 which registers with a similarly positioned lug 43 formed in each side of the gear housing, bolts 44 being provided to unite the parts together. By giving to the top wall of the gear housing a rectangular configuration, and by upturning the edges of the wall to furnish vertical flanges which lie between and abut against the vertical flanges of the supporting frame, a close and rigid union is effected between the housing and associated parts which journal the gearing. The supporting frame furnishes the connection with the bottom of the car body, and by securing the frame both to the car floor and to the front cross sill, a rigid union is effected between the structure of the car and the mounting for the gears. Thus the gears are mounted immediately below the front wall and cross sill of the car where rigidity of structure is greatest, but at the same time the rearward extension of the supporting frame affords adequate reinforcement which distributes the strains and affords resistance against the upward thrust occasioned by the pull of the brake chain.

While it is preferred, where extreme ruggedness of structure is desired, to provide a supporting frame of the U-shaped character indicated in Fig. 4 which affords continuity both in the vertical and lateral flanges comprising the frame, nevertheless where condition warrants, the frame shown in Fig. 5, 65 may be employed, or a frame composed of

separate straight angle bars may be employed without departure from the principle of the invention.

I claim:

1. In a mounting for brake gears in combination with the flooring and front end sill of a car, a supporting frame comprising two spaced angle bars extending longitudinally of the car and secured in part to the end sill and in part to the car flooring, and a gear mounting provided with upwardly protruding extensions lying in face contact with the vertical flanges of the supporting frame and secured thereto, substantially as described. 70

2. In a mounting for brake gears in combination with the flooring and front end sill of a car, a supporting frame comprising two spaced angle bars extending longitudinally of the car and secured in part to the end sill and in part to the car flooring, and a gear mounting provided with upwardly protruding extensions lying in face contact with the vertical flanges of the supporting frame and secured thereto, the gear mounting being positioned directly below the front end sill 80 of the car, substantially as described. 85

3. In a mounting for brake gears in combination with the flooring and front end sill of a car, a supporting frame comprising two spaced angle bars extending longitudinally 95 of the car and secured in part to the end sill and in part to the car flooring, and a gear mounting provided with upwardly protruding extensions lying in face contact with the vertical flanges of the supporting frame and secured thereto, the angle bars of the supporting frame extending rearwardly from the gear mounting and in contact with the car flooring, substantially as described. 100

4. In a mounting for brake gears in combination with the flooring and front end sill of a car, a supporting frame comprising two spaced angle bars extending longitudinally of the car and secured in part to the end sill and in part to the car flooring, and a gear mounting provided with upwardly protruding extensions lying in face contact with the vertical flanges of the supporting frame and secured thereto, the gear mounting being positioned directly below the front end sill 115 of the car, and the angle bars of the supporting frame extending rearwardly from the gear mounting and in contact with the car flooring, substantially as described. 120

5. In a mounting for brake gears in combination with the flooring and front end sill of a car, a supporting frame comprising two spaced angle bars extending longitudinally of the car and secured in part to the end sill and in part to the car flooring, a gear mounting provided with upwardly protruding extensions lying in face contact with the vertical flanges of the supporting frame and secured thereto, the angle bars of the supporting frame extending rearwardly from the 130

gear mounting and in contact with the car, and the angle bars of the supporting frame and the gear housing carried thereby extending forwardly of the end wall of the car, substantially as described.

6. In a mounting for brake gears in combination with the flooring and front end sill of a car, a supporting frame comprising two spaced angle bars extending longitudinally of the car and secured in part to the end sill and in part to the car flooring, and a gear mounting provided with upwardly protruding extensions lying in face contact with the vertical flanges of the supporting frame and secured thereto, the gear mounting being positioned directly below the front end sill of the car, the angle bars of the supporting frame extending rearwardly from the gear mounting and in contact with the car, and the angle bars of the supporting frame and the gear housing carried thereby extending forwardly of the end wall of the car, substantially as described.

7. In a mounting for brake gears in combination with the flanged front end sill of a car and the car flooring, a supporting frame comprising a pair of side rail angle bars connected at their rear ends to afford a continuous frame, the lateral flanges of the frame abutting against the bottom of the flanged front end sill and against the car flooring, means for securing the lateral frame flanges, respectively, to the sill and flooring, a gear housing provided with upwardly extending flanges lying between and secured to the forward end portions of the vertical flanges of the supporting frame, substantially as described.

of the frame, and a bracket secured below the gear housing and adapted to furnish a bearing for operating portions of the gear assembly, substantially as described.

40

8. In a mounting for brake gears in combination with the flanged front end sill of a car and the car flooring, a supporting frame comprising a pair of side rail angle bars connected at their rear ends to afford a continuous frame, the lateral flanges of the frame abutting against the bottom of the flanged front end sill and against the car flooring, means for securing the lateral frame flanges respectively to the sill and flooring, a gear housing provided with upwardly extending flanges lying between and secured to the forward end portions of the vertical flanges of the frame, a bracket secured below the gear housing and adapted to furnish a bearing for operating portions of the gear assembly, and a transversely extending angle plate having its flanges secured, respectively, to the end car sill and to the forwardly protruding ends of the supporting frame, substantially as de- 50

45

55

9. In a mounting for brake gears, in combination with the flooring of a car, a supporting frame comprising two spaced bars extending longitudinally of the car and secured to the car flooring, and a gear mounting provided with upwardly protruding extensions lying in face contact with the bars of the supporting frame and secured thereto, the frame extending a substantial distance to 70 the rear of the gear mounting.

ARTHUR F. O'CONNOR.
